United States Patent Office.

GEORGE PENRICE FARMER, OF BROOKLYN, NEW YORK, ASSIGNOR TO E. C. PRATT, BROTHER & CO., OF NEW YORK CITY.

Design No. 4,841, dated April 25, 1871.

DESIGN FOR A SHOW-CASE AND DRAWERS.

The Schedule referred to in these Letters Patent and making part of the same.

I, GEORGE PENRICE FARMER, of Brooklyn, county of Kings, State of New York, have invented or produced a Design for a Show-Case and Drawers combined, of which the following is a specification.

The figure in the accompanying drawing represents, in perspective, my design for show-case and drawers combined.

A is an oblong box, to which is hinged the glazed lid B, and in the top of the box is a recess, separated into compartments, *a*, *a*, and *b*, for the reception of needle-cases, &c.

Below this recess, and in the box A, are sliding drawers, D, the interior of each being separated by

partitions into compartments for the reception of spools, &c.

Claim.

The design for combined show-case and drawers, substantially as described, and as illustrated in and by the accompanying drawing.

In testimony whereof I have signed my name to this specification in the presence of two subscribing witnesses.
